United States Patent Office

Des. 233,831

Patented Dec. 3, 1974

233,831

AUTOMOBILE BODY

Henry G. Haga, Bloomfield Hills, Charles M. Jordan,
Franklin, William L. Mitchell, Bloomfield Hills,
and Jerry P. Palmer, Royal Oak, Mich., assignors to
General Motors Corporation, Detroit, Mich.

Filed Dec. 26, 1973, Ser. No. 427,850

Term of patent 7 years

Int. Cl. D12—08

U.S. Cl. D12—91

Fig. 3

Fig. 4

FIG. 1 is a side elevational view of an automobile body showing our new design, it being understood that the opposite side is a mirror image thereof;

FIG. 2 is a top plan view thereof;

FIG. 3 is a front elevational view thereof; and

FIG. 4 is a rear elevational view thereof.

The broken lines in the drawing are for illustrative purposes only.

We claim:

The ornamental design for an automobile body, substantially as shown and described.
